UNITED STATES PATENT OFFICE.

FREDERICK RECHT, OF NEW YORK, N. Y., ASSIGNOR TO FLORENCE RECHT, OF BROOKLYN, NEW YORK.

WINDOW-CAME.

1,092,784.

Specification of Letters Patent.

Patented Apr. 7, 1914.

Application filed June 19, 1912. Serial No. 704,694.

To all whom it may concern:

Be it known that I, FREDERICK RECHT, a citizen of the United States of America, and a resident of the borough of Brooklyn, in the city of New York, county of Kings, and State of New York, have invented certain new and useful Improvements in Window-Cames, of which the following is a specification.

10 The object of this invention is to produce a metallic glazing bar which will have the desired strength with a minimum of weight.

Further objects are to produce a glazing bar of a form which can be drawn through 15 a die and can readily be given irregular edges and a surface unevenness simulating the appearance of antique leads.

A further object is to provide a came in which cement can be retained to render the 20 joints with the glass weather proof.

In the accompanying sheet of drawings which forms a part of this application Figure 1 is a perspective of a glazing bar or came lead formed in accordance with my invention, Fig. 2 is a section through a portion 25 of a window in which the came is used for glazing, Fig. 3 is an elevation of a portion of the window with a corner of the glazing broken away.

20 The came consists of a heart *h* and caps *c c*. The caps at their middle lines join to and are integral with the heart. At their

edges the caps are thickened on the sides toward the glass, preferably by having bent over or inturned edges *e e*. Pockets are 35 thereby left behind the thickened edges and between the caps and the glass in which cement *d* can be retained to render the joints weather proof. The bending over is preferably irregular and the pockets afford an opportunity for mechanically breaking down 40 irregularly the faces of the caps to produce irregularity both of outline and surface.

In forming up a window the lights of glass will be joined and bounded by the cames as 45 shown. The transverse cames are preferably carried through the points of juncture with the vertical cames and let into the sash at either end. Each of these is preferably provided with a steel reinforcing bar *r* which is 50 laid next to the heart of the came.

What I claim as new, and desire to secure by Letters Patent of the United States, is—

A came-lead consisting of caps and a heart integral with each cap along the middle line 55 of its body, the edges of the caps being folded in upon themselves.

Signed by me at Brooklyn, N. Y., this 8th day of June, 1912.

FREDERICK RECHT.
